INVENTOR

R.E. Wise

BY Victor J. Evans

ATTORNEY

WITNESS:

UNITED STATES PATENT OFFICE.

JOHN FERTALLY, SR., OF WEATHERLY, PENNSYLVANIA.

PNEUMATIC CLEANER.

Application filed December 4, 1926. Serial No. 152,661.

This invention relates to pneumatic cleaners and one of its objects is to provide a cleaning tool primarily designed to remove dust, dirt and the like from a stone ballast, railroad tracks and other places.

Another object of the invention is to provide a pneumatic cleaner which is simple and inexpensive to manufacture, yet will perform its intended function in an expeditious and efficient manner with very little effort on the part of the operator.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a perspective view of the cleaner which forms the subject matter of the present invention.

Figure 2 is a sectional view taken on line 2-2 of Figure 2.

Referring to the drawings in detail the reference numeral 1 indicates the handle of the cleaner, which as shown in Figure 1 is a pipe threaded at its upper end to receive a conduit or the like (not shown) which is adapted to be in communication with a suitable source of compressed air. The handle 1 is provided with a valve 2 whereby the air can be controlled, and secured to the lower end of the handle is a T-joint 3 from which extends a pipe 4 arranged in alignment with the handle and has secured thereto a T-joint 5 having threaded therein pipe sections 6 which together with the T-joint 5 provides one of the air discharge members while the other air discharge member which likewise includes pipe sections identical to the sections 6 in construction, but for distinction are indicated by the reference numeral 7 and these pipe sections 7 are threaded in a T-joint 8. The air discharge member which

is formed from the sections 7 and T-joint 8, is arranged in parallelism with the first mentioned air discharge member and is in communication with the T-joint 3 through the instrumentality of a branch member 9 which includes an elbow and short pipes as clearly shown in Figure 1 of the drawings.

The pipe sections 6 and 7 are each provided with a lock nut 10 engaging the ends of the T-joints thereof as shown, so as to prevent the turning of the sections as will be readily apparent. The pipe sections are also provided with octagon shaped members 10' formed integral therewith intermediate their ends, whereby a wrench or like tool can be associated therewith for applying or removing the sections from their T-joints.

Depending from the pipe sections are inferiorly threaded projections 11 for receiving air nozzles 12.

From the above description and disclosure of the drawings, it will be obvious that I have provided a pneumatic cleaner that is very simple in construction and one that will clean a great surface in an efficient and expeditious manner with minimum expenditure of air and energy and with very little effort on the part of the operator. The force of the air passing through the nozzles 12 will be sufficient to blow dirt and other particles in the direction desired by the user and may pile the same whereby it can be removed by shovels or the like.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:

In a ballast cleaner, a pneumatic device formed from detachable pipe sections and comprising a tubular handle, a valve therein for controlling the passage through said handle, a T-joint secured to said handle, an elbow secured to the T-joint, a second T-joint in communication with the elbow,

pipe sections arranged in alignment with respect to each other and having their inner ends secured to the second T-joint upon opposite sides thereof, said aligned sections having their outer ends closed, lock nuts carried by the inner ends of the pipe sections and being engageable with the second T-joint, hollow projections formed integral with and depending from the hollow pipe sections, nozzles secured in said projections, and other nozzle carrying pipe sections similar to the aligned pipe sections depending from and in communication with the first mentioned T-joint.

15 In testimony whereof I affix my signature.
JOHN FERTALLY, Sr.
